UNITED STATES PATENT OFFICE.

ALFRED OLSON, OF SAN DIEGO, CALIFORNIA.

DUST-PAN.

SPECIFICATION forming part of Letters Patent No. 674,516, dated May 21, 1901.

Application filed September 1, 1900. Serial No. 28,831. (No model.)

To all whom it may concern:

Be it known that I, ALFRED OLSON, a citizen of the United States, residing at San Diego, in the county of San Diego and State of California, have invented new and useful Improvements in Dust-Pans, of which the following is a specification.

This invention relates to new and useful improvements in dust-pans; and its primary object is to provide a device of this character which is practically dustless, is simple in construction, durable, cheap to manufacture, and which is provided with a cover having means whereby it can be opened by hand or foot and locked in such position.

To these ends the invention consists in providing a handle for the tray of the pan, having slots or recesses therein for the reception of a hook formed upon a rod. This rod is loosely connected to the handle, which is secured to and extends backward from the cover of the tray and terminates in a loop, which incloses the handle and is adapted to be used when the lid is raised by foot.

The invention also consists in the further novel construction and combination of parts hereinafter more fully described and claimed, and illustrated in the accompanying drawings, showing the preferred form of my invention, in which—

Figure 1 is a side elevation of the device when open. Fig. 2 is a plan view thereof. Fig. 3 is a similar view showing the pan closed. Fig. 4 is a transverse section showing the hinges. Fig. 5 is a section through a portion of the pan.

Referring to the figures by numeral of reference, 1 is the tray of the pan, having a groove 2 therearound for the reception of the downwardly-bent edges of the cover 3. This cover is provided at the rear edge with an ear 4, which receives the ends of a wire 5. This wire is secured to the tray at each side of the ear 4 and is coiled, as at 6. The wire is secured to the lid at a point near the center thereof and serves to hold the same normally in closed position.

A handle 7 is hinged to the cover at 8 and terminates in a loop 9, which incloses the handle 10 of the device. A rod 11 is loosely secured to the handle 7 at its point of connection to the loop 9 and is provided with a hook

12 and a looped end 13, as shown. The hook is adapted to engage either one of two recesses or slots 14, formed within the handle, 55 and thereby retain the cover in open or partly-open position. When the lid is closed, the hook of the rod is not in engagement with the handle. When, however, it is desired to partly or entirely open the same, the hook 12 60 is placed into engagement with the proper slot 14.

It will be understood that when desired the lid can be raised by simply depressing the loop 9 of the handle by means of the foot. 65 This loop may, however, be dispensed with, if desired. It will be seen that the combined spring and hinge will keep the cover closed at all times.

In the foregoing description I have shown 70 the preferred form of my invention; but I do not limit myself thereto, as I am aware that modifications may be made therein without departing from the spirit or sacrificing the advantages thereof, and I therefore reserve 75 the right to make such changes and alterations as fairly fall within the scope of my invention.

I claim—

1. The combination with a tray, of a handle thereto having a recess therein, a cover to the tray, a handle to the cover, a loop to said handle inclosing the handle of the tray, and a hooked rod loosely secured to the handle of the cover and adapted to engage said 80 recess.

2. The combination with a tray having a groove therearound; of a handle thereto having a recess therein, a cover to the tray adapted to fit into the groove, a spring for holding 90 the cover normally closed, a handle to the cover, and a hooked rod loosely secured thereto and adapted to engage the recess.

3. The combination with a tray having a groove therearound; of a handle thereto having a recess therein, a cover to the tray adapted to fit into the groove, a spring for holding the cover normally closed, a handle to the cover, a loop to the handle inclosing the handle of the tray, and a hooked rod loosely secured to the handle of the cover and adapted to engage the recess. 95

4. The combination with a tray having a groove therearound; of a handle thereto hav-

ing a recess therein, a cover to the tray adapted to fit into the groove, a spring for holding the cover normally closed, a handle to the cover, an ear to the cover, a coiled wire secured to the tray at opposite sides of the ear and the ends thereof extending into the ear, said wire being also secured to the cover, a handle to the cover, a loop to the handle inclosing the handle of the tray, and a hooked

rod loosely secured to the handle of the cover to and adapted to engage the recess.

In testimony whereof I affix my signature in presence of two witnesses.

ALFRED OLSON.
